ROOF VENTILATOR

Lawrence L. Alldritt, 59 NW. 14th St., Miami 32, Fla.
Filed Sept. 3, 1959, Ser. No. 837,906
8 Claims. (Cl. 98—43)

The present invention relates to roof ventilators, and more particularly to such devices having a casing adapted to be secured to a roof as an upright outlet extension of an opening through the roof and having rotatable ventilating means operatively associated with the casing and power driven to exhaust air from the building.

Ventilating fans of this type are generally classified as either axial flow or centrifugal flow. In the former, air moves parallel to the axis of rotation of the fan; while in the latter air, moves radially outwardly of the axis of rotation of the fan.

Each of these two types has certain advantages and disadvantages. Axial flow fans, such as the usual propeller-type fans, have the advantage that they are relatively quiet in operation, but have the disadvantage that they cannot operate effectively against a substantial static head of pressure. Centrifugal fans have the advantage that they can operate against a substantial head of pressure, and in fact operate with greatest efficiency against pressure; but they have the disadvantage of noisy operation.

Both axial flow and centrifugal fans have been known for many years. More recently, a type of roof ventilator has come into use, which is characterized by a casing open at its top and bottom and adapted to be mounted on a roof over an opening therein, the casing being protected at its top by a rounded, downwardly concave hood or dome spaced above and laterally outwardly from the upper edge of the casing on all sides thereof, so that the hood and casing have the appearance of the cap and stem of a mushroom. Fan means associated with the hood or casing cause the air to flow up through the casing and downwardly outwardly on all sides of the casing between the hood and the casing.

These later hooded or domed roof ventilators have been both of the axial flow and of the centrifugal type. The axial flow type has been characterized for example by the use of a propeller fan wheel within the casing, as in U.S. Patent No. 2,571,513, October 16, 1951. The centrifugal type of domed roof ventilator is represented for example by a power driven rotating dome provided with vanes on the interior thereof, as in U.S. Patent No. 2,824,502, February 25, 1958.

The adaptation of both axial and centrifugal fans for use in domed roof ventilators has imposed additional disadvantages in connection with the operation of each type of fan. For example, the axial flow fan, when provided with a hood, not only remains incapable of drawing against an appreciable static head, as before, but is further rendered unsatisfactory by the fact that air is delivered axially against the dome and must be diverted so as almost to double back upon itself in its direction of movement, with consequent loss of efficiency. Indeed, the efficiency of an axial flow domed roof ventilator decreases the closer the dome is moved toward the fan wheel, so that the fan "mushes out," that is, suffers a sharp decrease in air delivery accompanied by a sharp rise in noise level. In the case of centrifugal domed roof ventilators, although the noise is reduced from that of a squirrel cage rotor, there is an added safety problem raised by the exposed, rapidly rotating dome, so that this type of ventilator may not be suitable for installation on schools and the like.

Accordingly, it is an object of the present invention to provide domed roof ventilators having the advantages

2

both of axial flow types and of centrifugal types, but without the disadvantages of either type.

It is another object of the present invention to provide domed roof ventilators having a number of desirable characteristics of centrifugal fans but operating at greatly reduced noise levels.

Still another object of the present invention is the provision of domed roof ventilators having the advantages of centrifugal fans but having a stationary dome.

10 A further object of the present invention is the provision of domed roof ventilators having the advantages of axial flow type fans but adapted to work against substantial heads of pressure.

15 A still further object of the present invention is the provision of domed roof ventilators having the advantages of axial flow fans but at the same time operating at increased efficiency by virtue of the presence of the dome.

Finally, it is an object of the present invention to provide a roof ventilator that is relatively inexpensive to manufacture, easy to install, operate and repair, efficient in operation, and rugged and durable in use.

Broadly stated, the present invention comprises the discovery that a domed roof ventilator having a propeller-type fan wheel can be made to take on all the advantages but none of the disadvantages of a centrifugal type fan by shaping, proportioning and disposing the blades relative to the axis of rotation, the upper edge of the casing and the dome as will be set forth hereinafter in greater detail.

Other objects, features and advantages of the present invention will become apparent from a consideration of the following description, taken in connection with the accompanying drawings, in which:

35 FIGURE 1 is a side cross-sectional view of a roof ventilator according to the present invention;

FIGURE 2 is a plan view of a roof ventilator according to the present invention but with the dome removed;

FIGURE 3 is an enlarged elevational view of a fan wheel according to the present invention, viewed perpendicular to the axis of rotation of the fan wheel, the fan wheel being in that rotated position in which that vertical plane is viewed edgewise which includes the axis of rotation of the fan wheel and bisects the mounting bracket of the blade shown on the near side;

FIGURE 4 is a view similar to FIGURE 3 but showing the fan wheel in a further rotated position and with one blade shown in section along the line 4—4 of FIGURE 3;

FIGURE 5 is a plan view of the fan wheel of the present invention;

FIGURE 6 is an oblique view of the fan wheel of the present invention, with one blade viewed broadside, that is, perpendicular to the plane of the blade at the section line 4—4 of FIGURE 3; and

55 FIGURE 7 is a cross-sectional view of a propeller fan blade according to the present invention, taken on the line 7—7 of FIGURE 6.

Referring now to the drawings in greater detail, there is shown a roof ventilator indicated generally at 1 and comprising a round casing 3 mounted with its axis vertical on a roof 5 over an opening 7 therein. Casing 3 is provided with the usual flashing at its lower end whereby it is adapted to the rectangular contour of opening 7. Casing 3 may be in the form of a truncated conical sheet, as shown, or in the form of a cylindrical sheet, or otherwise rounded; and the term "round" is intended to comprehend all of these shapes. Casing 3 terminates at its upper end in an upper edge 9 which is circular.

An electric motor 11 is mounted coaxially and concentrically in casing 3 by means of a bracket 13 having attachment to the side walls of casing 3 forming a cradle

for the motor. Motor 11 is of course provided with electrical wires (not shown) for appropriate connection to a source of electric power. Motor 11 has a rotatable drive shaft 15 extending upwardly therefrom coaxially concentrically with casing 3 and motor 11. It will be understood that instead of mounting motor 11 coaxially, it can be mounted to one side of the casing and belt-connected to a fan shaft coaxial with the casing.

Mounted concentrically and coaxially above casing 3, and spaced therefrom, is a rounded, downwardly concave hood 17 supported on support brackets 19 which in turn are mounted on the outer upper surfaces of casing 3 and terminate in upper ends which extend through holes in hood 17 and are provided with removable fasteners 21 detachably to secure hood 17 in place on brackets 19. In this way, hood 17 is mounted fixedly on casing 3 and is spaced above and laterally outwardly from the upper edge 9 of casing 3 on all sides thereof.

A rotatable fan wheel 23 of the propeller type has a central hub 25 by which it is mounted coaxially for rotation on the upper end of drive shaft 15 of motor 11. Hub 25 has a plurality of brackets 27 extending generally radially outward therefrom and spaced peripherally thereabout, each bracket being pierced with a plurality of holes for the reception of rivets 29 by which a propeller fan blade 31 is secured fixedly on the upper side of each bracket 27.

Blades 31 thus rotate about the common axis 33 of casing 3, drive shaft 15, hood 17, fan wheel 23 and hub 25, and are inclined forwardly downwardly, in their direction of movement while exhausting air, at a relatively steep average pitch.

A major distinguishing feature of the disposition of blades 31, however, is that in addition to their pitch relative to their direction of movement, they are given a second pitch radially of their axis of rotation. Specifically, in addition to being inclined forwardly downwardly in their direction of rotation in the usual manner of fan blades, they are inclined radially outwardly downwardly with regard to their axis of rotation. Brackets 27 are roughly bisymmetric; and this second pitch will be more particularly appreciated when it is recognized that the vertical plane which includes the axis of rotation of the fan wheel and which substantially bisects brackets 27, intersects the upper surface of blade 31 in an imaginary line 35 which forms a negative acute angle with the horizontal and is inclined downwardly outwardly from line 33. Thus, in FIGURE 3, line 35 coincides with section line 4-4, so that FIGURE 3 is a view edgewise of the plane which intersects the upper surface of blade 31 in line 35. Stated another way, the upper surface of blade 31 adjacent line 35 can never be viewed edgewise in a horizontal plane but only obliquely.

Line 35, although imaginary, is a very important reference point for further description of the blade. This line may be considered to divide blades 31 arbitrarily into an upper portion 37 and a lower portion 39. Another important feature of the present invention resides in the fact that upper portion 37 is upwardly concave and lower portion 39 is downwardly concave. This concavity, however, is a two dimensional curve rather than the usual three dimensional curve of fan blades. Specifically, the upper surface of upper portion 37 is comprised of an infinite number of straight lines parallel to each other and parallel to imaginary line 35. The same is true of the upper surface of lower portion 39. Moreover, in the illustrated embodiment, imaginary line 35 marks in effect the flex point of the cross-sectional contour of blade 31, that is, the line of camber reversal between upper and lower portions 37 and 39. This is to say that the upper surface of blade 31 is essentially unplanar at least for small distances on either side of imaginary line 35. Below line 35, therefore, the upper surface of blade 31 is downwardly concave and above line 35 it is upwardly concave; but at line 35 the curves meet

and reverse. Although line 35 and the line of camber reversal are shown in the illustrated embodiment as being one and the same straight line, it will of course be understood that small variations from this relationship can be tolerated without departing from the ambit of the invention. Thus, the two lines need not be precisely coincident nor precisely parallel nor precisely straight in order to achieve the essential operative characteristics of the present invention.

It should also be noted that, as shown in FIGURE 7, blade 35 has an edgewise profile which at no point is of greater width than the thickness of the material of blade 31. Also, it should be noted that although the pitch of blade 31 in its direction of movement is steep at all places, it is at a minimum adjacent imaginary line 35 and at a maximum on both sides of line 35.

Indeed, the pitch progressively increases from line 35 to the portions of the blade on either side thereof which are farthest from line 35. Thus, portion 41, which is the portion of blade 31 farthest from line 35, is the blade portion of greatest pitch above line 35; while portion 43, which is that part of lower portion 39 farthest from line 35, is the blade portion of maximum pitch on the other side of line 35. It should also be noted that portion 41 is spaced radially outward from axis 33 a substantially greater distance than is portion 43. Also, portions 41 and 43 are spaced apart from each other a distance considerably greater than the length of line 35. Also, it should be noted that the greatest arc subtended by blade 31 is more than 360° divided by the number of blades 31, so that an upper portion of each blade overlies a lower portion of each succeeding blade. Furthermore, it should be noted that the area of the upper surface of portion 37 is considerably greater than the area of the upper surface of portion 39.

Finally, it should be noted that the outer edge of blade 31 is a fairly smooth curve, as indicated at 45. But continuing upwardly about this curve, it will be noted that the smooth continuity of the curve is broken at portion 41 and the fan blade is of substantially less area than if the smooth curve 45 were continued beyond portion 41. In effect, the blade is cut away as at 47, the edge of 47 being convexly rounded but still recessed relative to a continuation of curve 45.

The shape and orientation of blades 31 have been discussed; and further important features of the invention reside in the orientation and disposition of the blades relative to the casing and hood. Thus, another important feature of the invention is that line 35 is above upper edge 9 of the casing. Although line 35 extends radially downwardly outward, it never crosses or extends within that circular line which marks upper edge 9. Also, it should be noted that blades 31 extend a substantial distance radially outward beyond upper edge 9, the point of farthest outward extension of blades 31 being located on upper portion 37 thereof. Moreover, a portion only of lower portion 39 of blade 31 extends down into casing 3 below upper edge 9. At the other or upper end of blade 31, it should be noted that portion 41 is that part of the blade which most closely approaches the underside of hood 17. From that point of closest approach, the outer edge of blade 31 and the underside of hood 17 progressively diverge from each other.

It will thus be observed that although the lower portions of blades 31 serve to some extent as an axial flow fan, the major portion of the blades is given over to operation as a centrifugal fan. Thus, the major portion of the blades coacts with hood 17 in much the same manner as a squirrel cage rotor coacts with its surrounding scroll. From a visual inspection of the device, it is difficult to recognize that the upper portions of the blades are in effect serving as a centrifugal fan in cooperation with the hood; but it will be realized that this is true when it is seen how the above-described features are directed toward securing this operation. Specifically, por-

tion 43 and the lower end of lower portion 39 in effect dig down into the casing to serve efficiently to induce axial flow; but from then on, the flow of the air becomes increasingly centrifugal in character by the interaction of the specially formed and oriented blade and the hood. The positioning of imaginary line 35 above upper edge 9 assures that the upper portion of the blade will coat with the hood as a scroll rather than with the casing as in an axial flow device. The negative radial outward pitch of the blades, evidenced by the negative inclination of line 35, is an extremely important feature, assuring as it does that a radially outward impulse be imparted to the air in the manner of a centrifugal fan. The upward concavity of upper portion 37 of the blades along an infinite number of straight lines parallel to line 35 imparts a radially downward and outward component of thrust to the air which further turns the air outward and downward in cooperation with the curvature of the hood. The different radial distances of portions 43 and 41, the former being closer to the axis of rotation than the latter, assures that as the air passes from the former to the latter, it is given a further radial outward impulse; and the portion cut away as at 47 assures that the upper tip comprising portion 41 will be radially outwardly positioned for this purpose. The overhang of portion 37 radially outward beyond upper edge 9 also coats with the differential radial spacing of portions 41 and 43 further to achieve the same result. Also, the progressively increasing pitch upward from line 35 to portion 41, in combination with the radially outward negative pitch, assures that the outward impulse on the air increases as it moves up along blade 31, so that a minimum of air is thrown against hood 17. Indeed, air is travelling substantially parallel to the under surface of the hood when it reaches that height. The great length of blade 31 between portions 41 and 43, relative to the length of line 35, also assures that blade 31 will reach sufficiently far down into casing 3 to perform its axial function, but at the same time will reach up sufficiently close to hood 17 to cause hood 17 to coat therewith in the manner of a scroll. Indeed, the divergence of the hood and blade from closest portion 41 downwardly outwardly about curve 45 corresponds functionally to the divergence between a squirrel cage rotor and its scroll from the cutoff point about the rotor to the discharge.

Precise dimensions cannot be given for the present invention, as these will vary depending on a number of factors such as casing size, hood diameter, fan wheel diameter and speed, and static pressure head. By way of example, however, it might be noted that for a well-supplied airspace without ductwork, a ventilator with a 30-inch casing upper diameter, a 35½-inch fan wheel diameter, a 54-inch inside diameter of the dome at the bottom thereof, an angle for line 35 of -12° from the horizontal, a speed of 1180 r.p.m., and a least distance between fan blades and dome of 1½ inch, are typical of the invention. It is not true that the very least possible spacing between portions 41 and the hood is necessarily the best spacing. The best spacing must be determined with due regard to the other variables listed above. In general, however, the faster the fan speed the lower and closer to the blades should be the hood.

The centrifugal nature of the operation of ventilators according to the present invention is demonstrable by a simple experiment in which the hood is removed and the efficiency of the unit is computed with the unit acting solely as an axial flow fan. The hood is then held several feet above the unit, so that the hood furnishes an obstruction to axial flow but does not yet coat with the blades to induce centrifugal flow. The efficiency is again computed and it is noted that this efficiency is lower than the first efficiency. Finally, the hood is lowered into operative position, with portions 41 closely adjacent the under side of the hood and the lower edge of the hood at least as low as upper edge 9 of casing 3. A sharp rise

in efficiency is noted, to a level above the efficiency with the hood removed entirely. In the first step, air was moving axially only. In the second step, the fan was loaded with an impediment in the air stream. But in the third step, the fan blades and the hood were coacting to induce centrifugal flow at high efficiency. Hence, in contrast to previous fixed dome roof ventilators, in which the hood bodily deflects the air and reduces the efficiency of the device, the present invention is characterized in that the hood and the blades coat together to induce centrifugal flow at greater efficiency than if the hood were removed. Another characteristic of the present invention which demonstrates its centrifugal nature is the absence of overloading when the air supply is shut off. Shutting off the air supply of an axial flow fan overloads the motor and soon burns it out; but shutting off the air supply of the present invention actually unloads the motor, as is characteristic of most centrifugal fans. Furthermore, adding a dome to an axial flow fan raises the noise level; but adding the dome to the present fan actually reduces the noise level in the same manner as adding a scroll to a squirrel cage fan rotor.

From a consideration of the foregoing, it will be obvious that all the initially recited objects of the present invention have been achieved.

It is to be understood that the appended claims are to be accorded a range of equivalents commensurate in scope with the advance made over the prior art.

What is claimed is:

- 30 1. In a power driven roof ventilator including a round casing open at its top and bottom and adapted to be mounted with its axis vertical on a roof over an opening therein and terminating upwardly in an upper edge, a rounded, downwardly concavely curved hood fixedly mounted coaxially above the casing and extending laterally outward beyond said upper edge of the casing on all sides of the casing, a fan wheel mounted for rotation beneath the hood coaxially of the casing and including a plurality of outwardly extending propeller fan blades, and power means for rotating the fan wheel about said axis; the improvement comprising the fan blades having an upper portion having an upwardly concave upper surface made up of an infinite number of parallel straight lines one of which passes through the axis of rotation of the fan wheel and is inclined downwardly outwardly at an acute angle to the horizontal and is disposed above said upper edge, at least a portion of the blade extending below said upper edge.
- 35 2. Apparatus as claimed in claim 1, said upper portion extending a substantial distance laterally outwardly beyond said upper edge.
- 40 3. Apparatus as claimed in claim 1, the hood and the blades approaching each other most closely at the portion of said upper portion farthest from said one line.
- 45 4. In a power driven roof ventilator including a round casing open at its top and bottom adapted to be mounted with its axis vertical on a roof over an opening therein and terminating upwardly in an upper edge, a rounded, downwardly concavely curved hood fixedly mounted coaxially above the casing and extending laterally outward beyond said upper edge of the casing on all sides of the casing, a fan wheel mounted for rotation beneath the hood coaxially of the casing and including a central hub having a plurality of fan blade mounting brackets extending outwardly therefrom and propeller fan blade mounted on and extending outwardly from each said bracket, and power means for rotating the fan wheel about said axis; the improvement comprising the fan blades being reverse cambered and having a downwardly concave lower portion and an upwardly concave upper portion and being inclined downwardly outwardly such that a plane which includes said axis and which substantially bisects a said bracket intersects the upper surface of the associated blade in a downwardly outwardly inclined line that is
- 50 5. In a power driven roof ventilator including a round casing open at its top and bottom adapted to be mounted with its axis vertical on a roof over an opening therein and terminating upwardly in an upper edge, a rounded, downwardly concavely curved hood fixedly mounted coaxially above the casing and extending laterally outward beyond said upper edge of the casing on all sides of the casing, a fan wheel mounted for rotation beneath the hood coaxially of the casing and including a central hub having a plurality of fan blade mounting brackets extending outwardly therefrom and propeller fan blade mounted on and extending outwardly from each said bracket, and power means for rotating the fan wheel about said axis; the improvement comprising the fan blades being reverse cambered and having a downwardly concave lower portion and an upwardly concave upper portion and being inclined downwardly outwardly such that a plane which includes said axis and which substantially bisects a said bracket intersects the upper surface of the associated blade in a downwardly outwardly inclined line that is
- 55 6. In a power driven roof ventilator including a round casing open at its top and bottom adapted to be mounted with its axis vertical on a roof over an opening therein and terminating upwardly in an upper edge, a rounded, downwardly concavely curved hood fixedly mounted coaxially above the casing and extending laterally outward beyond said upper edge of the casing on all sides of the casing, a fan wheel mounted for rotation beneath the hood coaxially of the casing and including a central hub having a plurality of fan blade mounting brackets extending outwardly therefrom and propeller fan blade mounted on and extending outwardly from each said bracket, and power means for rotating the fan wheel about said axis; the improvement comprising the fan blades being reverse cambered and having a downwardly concave lower portion and an upwardly concave upper portion and being inclined downwardly outwardly such that a plane which includes said axis and which substantially bisects a said bracket intersects the upper surface of the associated blade in a downwardly outwardly inclined line that is
- 60 7. In a power driven roof ventilator including a round casing open at its top and bottom adapted to be mounted with its axis vertical on a roof over an opening therein and terminating upwardly in an upper edge, a rounded, downwardly concavely curved hood fixedly mounted coaxially above the casing and extending laterally outward beyond said upper edge of the casing on all sides of the casing, a fan wheel mounted for rotation beneath the hood coaxially of the casing and including a central hub having a plurality of fan blade mounting brackets extending outwardly therefrom and propeller fan blade mounted on and extending outwardly from each said bracket, and power means for rotating the fan wheel about said axis; the improvement comprising the fan blades being reverse cambered and having a downwardly concave lower portion and an upwardly concave upper portion and being inclined downwardly outwardly such that a plane which includes said axis and which substantially bisects a said bracket intersects the upper surface of the associated blade in a downwardly outwardly inclined line that is
- 65 8. In a power driven roof ventilator including a round casing open at its top and bottom adapted to be mounted with its axis vertical on a roof over an opening therein and terminating upwardly in an upper edge, a rounded, downwardly concavely curved hood fixedly mounted coaxially above the casing and extending laterally outward beyond said upper edge of the casing on all sides of the casing, a fan wheel mounted for rotation beneath the hood coaxially of the casing and including a central hub having a plurality of fan blade mounting brackets extending outwardly therefrom and propeller fan blade mounted on and extending outwardly from each said bracket, and power means for rotating the fan wheel about said axis; the improvement comprising the fan blades being reverse cambered and having a downwardly concave lower portion and an upwardly concave upper portion and being inclined downwardly outwardly such that a plane which includes said axis and which substantially bisects a said bracket intersects the upper surface of the associated blade in a downwardly outwardly inclined line that is
- 70 9. In a power driven roof ventilator including a round casing open at its top and bottom adapted to be mounted with its axis vertical on a roof over an opening therein and terminating upwardly in an upper edge, a rounded, downwardly concavely curved hood fixedly mounted coaxially above the casing and extending laterally outward beyond said upper edge of the casing on all sides of the casing, a fan wheel mounted for rotation beneath the hood coaxially of the casing and including a central hub having a plurality of fan blade mounting brackets extending outwardly therefrom and propeller fan blade mounted on and extending outwardly from each said bracket, and power means for rotating the fan wheel about said axis; the improvement comprising the fan blades being reverse cambered and having a downwardly concave lower portion and an upwardly concave upper portion and being inclined downwardly outwardly such that a plane which includes said axis and which substantially bisects a said bracket intersects the upper surface of the associated blade in a downwardly outwardly inclined line that is
- 75 10. In a power driven roof ventilator including a round casing open at its top and bottom adapted to be mounted with its axis vertical on a roof over an opening therein and terminating upwardly in an upper edge, a rounded, downwardly concavely curved hood fixedly mounted coaxially above the casing and extending laterally outward beyond said upper edge of the casing on all sides of the casing, a fan wheel mounted for rotation beneath the hood coaxially of the casing and including a central hub having a plurality of fan blade mounting brackets extending outwardly therefrom and propeller fan blade mounted on and extending outwardly from each said bracket, and power means for rotating the fan wheel about said axis; the improvement comprising the fan blades being reverse cambered and having a downwardly concave lower portion and an upwardly concave upper portion and being inclined downwardly outwardly such that a plane which includes said axis and which substantially bisects a said bracket intersects the upper surface of the associated blade in a downwardly outwardly inclined line that is

disposed above said upper edge, at least a portion of the blade extending below said upper edge.

5. Apparatus as claimed in claim 4, the portion of the blade closest to the hood being the portion of the blade of greatest pitch.

6. In a power driven roof ventilator including a round casing open at its top and bottom and adapted to be mounted with its axis vertical on a roof over an opening therein and terminating upwardly in an upper edge, a rounded, downwardly concavely curved hood fixedly mounted coaxially above the casing and extending laterally outward beyond said upper edge of the casing on all sides of the casing, a fan wheel mounted for rotation beneath the hood coaxially of the casing and including a plurality of outwardly extending propeller fan blades, and power means for rotating the fan wheel about said axis; the improvement comprising the fan blades being reverse cambered and having a downwardly concave lower portion and an upwardly concave upper portion and having upper surfaces at least partly made up of an infinite number of straight lines, one of said lines passing through the axis of rotation and being inclined downwardly at an acute angle, said line being disposed above said upper edge, at

10
15
20

least a portion of the blade extending below said upper edge.

7. Apparatus as claimed in claim 6, the blade on the upper side of said line extending a substantial distance laterally outwardly beyond said upper edge.

8. Apparatus as claimed in claim 6, said straight lines above said one line being parallel to each other and to said one line.
